UNITED STATES PATENT OFFICE.

FRANK THEODORE WILLIAMS, OF MERIDEN, CONNECTICUT, ASSIGNOR TO
THE EDWARD MILLER & COMPANY, OF SAME PLACE.

DESIGN FOR A GAS-BURNER.

SPECIFICATION forming part of Design No. 25,418, dated April 21, 1896.

Application filed January 27, 1896. Serial No. 577,082. Term of patent 14 years.

To all whom it may concern:

Be it known that I, FRANK THEODORE WILLIAMS, a citizen of the United States, residing at Meriden, Connecticut, have invented and
5 produced a Design for Gas-Burners, of which the following is a specification.

The accompanying drawing represents my burner in perspective.

The invention relates to a design for an Argand gas-burner; and the design consists in the configuration thereof, as shown in the illustration.

Referring to the drawing, 1 designates a substantially vertical flange; 2, a horizontal flange; 3, a nearly vertical imperforate wall; 4, an arched annular perforate cap above the wall 3, the peripheral top clearly showing the perforations; 5, a horizontal perforate annulus; 6, a central perforate nearly conical por-

tion filling the entire space within the annulus 5; 7, a dish-shaped perforate portion surrounding the portion 6; 8, a cap covering the dish-shaped portion 7.

The leading feature of my design is the imperforate wall 3 in connection with the perforate portions 4, 5, 6, and 7, the whole surrounded by the cap 8, comprising the unitary design shown.

What I claim as my invention, and desire to secure by Letters Patent of the United States, is as follows:

The design for a gas-burner, substantially as shown and described.

FRANK THEODORE WILLIAMS.
